LIQUID TRANSMISSION.

1,314,153.

Specification of Letters Patent. Patented Aug. 26, 1919.

Application filed August 21, 1918. Serial No. 250,871.

To all whom it may concern:

Be it known that I, EUGÈNE SCHNEIDER, a citizen of the French Republic, and a resident of 42 Rue d'Anjou, Paris, France, have 5 invented a new and useful Improvement in Liquid Transmission, which invention is fully set forth in the following specification.

The present invention relates to apparatus for producing movement by means of a fluid under pressure, and it has for its object to provide improved apparatus of this type for transmitting motion to a suitable member, such as a piston or diaphragm movable in a cylinder and controlling by its spindle or rod, or by that rod and a counter or tail rod, mechanism such as clutch members, valves, hinged flaps or other contrivances.

20 The improved apparatus is characterized by the fact that the bodies of liquid, receiving pressure which is transmitted respectively to the two faces of the reciprocating piston, are separate one from the other; 25 main constant in volume and are each contained in the compartment between a face of the piston and the corresponding end of the cylinder and a chamber which communicates adjacent its bottom with said 30 compartment. The space above the surface of the liquid in each chamber, adjacent its upper end, can be placed alternately in communication with a conduit for the admission of a fluid under pressure to the said 35 space and a conduit that serves for the exhaust of the fluid so admitted.

According to this invention, the distributing devices, by which the spaces above the surface of the liquid in the two chambers 40 are placed alternately in communication with the admission and exhaust conduits, are so disposed that they may be operated by a single lever, whereby either one of the chambers may be placed in communication 45 with the admission conduit while the other is at the same time automatically placed in communication with the exhaust conduit.

The invention is capable of receiving a variety of mechanical expressions, one of which 50 is shown on the accompanying drawing, but it is to be expressly understood that the drawing is for purposes of illustration only and is not to be construed as a definition of the limits of the invention, reference being 55 had to the appended claims for that purpose.

Said drawing represents a sectional elevation of one embodiment of the invention.

In said drawing, A denotes a piston that moves in a fluid-tight manner in a cylinder B, and transmits, by means of its spindle or 60 rod a and also, if need be, by a tail rod a', the reciprocating movements which are given to it by a liquid under pressure. The cylinder B communicates, adjacent its two 65 ends as at b and b' respectively, with the two chambers C and C', which, though they may be coupled together or be integrally formed, constitute separate compartments. Communication is established between the inlet 70 passages b and b' and the lower part of the chambers C and C' by means of the tubes D and D', each of which is fitted with a cock d or d' for controlling the volume of the flow of liquid through said tubes.

A body of liquid, which always remains 75 constant in volume, is contained in the space above the upper face of piston A and in chamber C, the communicating tube D and the upper compartment of cylinder B being maintained constantly full and the 80 liquid in chamber C varying in level according to the position of the piston. Another separate body of liquid is contained in the space below the lower face of piston A and in chamber C', the lower compartment 85 of cylinder B and tube D' being maintained constantly full and the level of the liquid in chamber C' varying according to the position of the piston.

Each of the chambers C, C' communicates 90 adjacent its upper part, at c and c' respectively, with a distributing device adapted to place the space above the surface of the liquid in chambers C and C' alternately in communication with a supply of fluid under 95 pressure and with an exhaust outlet.

In the form shown, each distributor is arranged to maintain the space above the liquid in the chambers normally in communication with the exhaust outlet so long 100 as the distributing device is not manually or otherwise actuated, and to reestablish automatically this condition when the controlling member ceases to act. The distributors are so disposed that they can be 105 alternately actuated by a single member, such as a lever, common to both.

E and E' denote tubes or ducts communicating with a source of gas or other fluid under pressure. The inlets for the fluid to 110

the passages c , c' are normally closed by valves G , G' held to their seats by springs g , g' respectively. Each of these valves is provided with an axial conduit H , H' which 5 normally maintains communication between the passages c , c' and the exhaust outlets F , F' . The valves may be raised by one or the other of the arms of a lever I , I' pivoted at i which operates corresponding push rods 10 J , J' normally retained out of action, or away from the corresponding valves, by springs j , j' . Each push rod, the movements of which are limited by a stop K , K' , when it raises a valve also closes the lower end of 15 the axial conduit therethrough, thus cutting off communication between the chamber and the exhaust outlet.

The apparatus operates as follows:—
The lever I — I' being operated, for example, in the direction of the arrow X , acts on the push rod J' and raises thereby the valve G' . Air or gas under pressure, admitted through the tube E' , passes through the opening around the lifted valve G' and 20 the passage c' into the chamber C' . It presses upon the liquid therein causing some of it to flow through the tube D' into cylinder B where it acts on piston A which is displaced in the direction of the arrow Y . 25 Meanwhile, the arm I of the lever being lowered, the push rod J , under the action of its spring j , descends and allows the valve G to engage its seat thereby opening the conduit H through which the air or gas 30 under pressure in the upper part of chamber C escapes to the atmosphere by means of the exhaust orifice F .

The pressure in chamber C being relieved, as piston A rises, the liquid from the upper compartment of cylinder B returns 40 through tube D into the chamber C .

If lever I — I' be moved in the reverse direction, valve G will be raised and valve G' will return to its seat. The pressure 45 exerted on the liquid in chamber C will be transmitted to the upper face of piston A and move the latter in a direction reverse to that indicated by the arrow Y ; while the pressure in chamber C' will be relieved and 50 the liquid from the lower compartment of cylinder B return to chamber C' .

By operating the cocks d , d' , the cross sectional area of the passages through tubes D , D' can be modified and the speed of 55 flow of the liquid therethrough varied, and consequently the speed at which the apparatus works can be regulated.

With the aid of suitable independent cocks, several cylinders, such as B , can be 60 supplied with liquid from a single group of chambers, such as chambers C , C' , if properly provided with distributing devices.

The lever I — I' can be operated by hand or mechanically. When the lever is turned into its mean position, indicated in broken lines, the apparatus will be at rest, with no pressure acting on the surface of the liquid in chambers C , C' as the space in the upper part of both is in communication with the exhaust outlets F , F' . 65

While the embodiment illustrated on the drawing has been described with considerable particularity, it is to be understood that the invention is not to be restricted thereto, as the same is capable of receiving a variety of mechanical expressions. Reference is to be had to the claims hereto appended for a definition of the limits of the invention. 70

What is claimed is:—

1. In combination with a cylinder and piston, liquid-containing chambers, ducts constituting means of communication between the compartments in the cylinder on either side of the piston and the respective chambers, said ducts and compartments being constantly full of liquid, fluid passages in continuous communication with said chambers above the surface of the liquid therein, valves controlling the admission of fluid under pressure to said passages, passages extending axially through said valves and in continuous communication with said first-named passages, exhaust outlets normally in communication with said axial passages, 85 and controlling means for opening either of said valves and simultaneously closing the axial passage therethrough. 90

2. In combination with a cylinder and piston, liquid-containing chambers, ducts constituting means of communication between the compartments in the cylinder on either side of the piston and the respective chambers, said ducts and compartments being constantly full of liquid, fluid passages in continuous communication with said chambers above the surface of the liquid therein, valves controlling the admission of fluid under pressure to said passages, passages extending axially through said valves and in continuous communication with said first-named passages, exhaust outlets normally in communication with said axial passages, 95 and controlling means for opening either of said valves and simultaneously closing the axial passage therethrough. 100

3. In combination with a cylinder and piston, liquid-containing chambers, ducts constituting means of communication between the compartments in the cylinder on either side of the piston and the respective chambers, said ducts and compartments being constantly full of liquid, fluid passages in continuous communication with said chambers above the surface of the liquid therein, valves controlling the admission of fluid under pressure to said passages, 105 passages extending axially through said valves and in continuous communication with said first-named passages, exhaust outlets normally in communication with said axial passages, movable members adapted to engage the respective valves to first close the axial passages therethrough and thereafter move said valves, and controlling means adapted to actuate either of said movable members. 110

In testimony whereof I have signed this specification.
